[57] **ABSTRACT**

A solid state-vacuum wideband amplifier is provided. The amplifier includes an electron source adapted to emit electrons in response to an rf signal and wideband rf signal input means connected to the electron source. The amplifier further includes means for accelerating the electrons toward an electron beam semiconductor current amplifying device and means for focusing and accelerating the electrons so that they will bombard the amplifying device. Wideband rf signal output means are connected to the amplifying device.

SOLID STATE-VACUUM WIDEBAND AMPLIFIER

The invention described herein may be manufactured and used by or for the Government for governmental purposes without the payment of any royalties thereon or therefor.

BACKGROUND OF THE INVENTION

The present invention relates to wideband amplifiers and more particularly to a solid state-vacuum wideband amplifier.

Heretofore, amplifiers capable of operating within a range from substantially dc to 800 or more megahertz utilized a hot cathode and a traveling wave deflection system. Such devices have several drawbacks stemming from their construction. These drawbacks include the large physical size necessitated by the traveling wave deflection system; environmental problems resulting from the hot cathode and the expenses involved in their manufacture and production.

In view of the above, it is the principal object of the present invention to provide a solid state-vacuum wideband amplifier.

SUMMARY OF THE INVENTION

The above and other beneficial objects and advantages are attained in accordance with the present invention by providing a solid state-vacuum amplifier which includes an electron source adapted to emit electrons in response to an rf signal and wideband rf signal input means connected to the electron source. The amplifier further includes means for accelerating the electrons toward an electron beam semiconductor current amplifying device and means for focusing and accelerating the electrons so that they will bombard the amplifying device. Wideband rf signal output means are connected to the amplifying device.

BRIEF DESCRIPTION OF THE DRAWING

In the accompanying drawing:

FIG. 1 is the schematic representation of the wideband amplifier of the present invention;

FIG. 2 is an enlarged perspective view of a first embodiment of cold cathode and strip-line connector for use in the wideband amplifier of FIG. 1;

FIG. 3 is a perspective and longitudinal sectional view of a second embodiment of a cold cathode and strip-line connector for use in the wideband amplifier of FIG. 1, taken in part along reference lines 3-3 of fragmentary FIG. 4 in the direction indicated by the arrows; for purposes of clarity, section lines have been omitted from FIG. 3; and,

FIG. 4 is an enlarged perspective fragmentary view of the cathode end of FIG. 3.

DETAILED DESCRIPTION OF THE PREFERRED EMBODIMENT

The present invention is illustrated in the accompanying drawing wherein similar components bear the same reference numeral throughout the several views. Reference is first made to FIG. 1 wherein the wideband amplifier of the present invention includes a novel solid state-vacuum component 10 having a cold cathode 12 coupled by capacitor 14 to an rf signal source 16. In response to rf signal to component 10, cathode 12 emits electrons which are accelerated toward an electron beam semiconductor (EBS) diode 18 through a focus-

ing electrode 20. The electrons emitted by cathode 12 are accelerated toward diode 18 by a high voltage (on the order of 10-15kv) low current power supply 22. A variable power supply 24 drives the focusing electrodes 20 to direct electrons emitted by the cold cathode to the metallic connection 26 on the p layer of the electron beam semiconductor diode 18. The diode 18 is connected to a low voltage high current power supply 28 through a load resistor 30 across which the amplified rf output signal appears.

FIG. 2, 3 and 4 show details of two different embodiments of cold cathode 12, coupling capacitor and the connector 32 between the cold cathode 12 and rf signal source 16.

15 In the first embodiment shown in FIG. 2, the connector 32 is a strip-line 34 comprising an elongated base member 36 of dielectric material carrying a pair of parallel coextensive conductor strips 38 and 40. The strip-line 34 overlies an electron emitting source comprising 20 an elongated member 42 formed of dielectric material. The top surface of member 42 had applied to it in the active area designated by the bracket 45, an SnO_2 layer 44. A first conductive comb 46 and a second conductive comb 48 overlies the dielectric material and the SnO_2 layer. The combs 46 and 48 have parallel side-by-side extensions 50 and 52 underlying end portions of conductor strips 38 and 40 respectively near the end 54 of strip-line 34. Conductive comb 46 has teeth 56 that interdigitate with similar teeth 58 of comb 48 in the active area 45. Electrons are emitted between the interdigitated teeth in response to an rf signal applied to conductive combs 46 and 48. When an rf signal is applied to conductor strips 38 and 40 of strip-line 34 the signal is capacitively coupled to conductive combs 46 and 48 through the dielectric base member 36. The size of the metal teeth and their number per unit length of the conductive combs are designed for the emission density required for a particular application.

40 In the second embodiment of the present invention depicted in FIGS. 3 and 4, the electron source comprises an optoelectronic cold cathode 60 (such devices have been developed by and are available from the Radio Corporation of America) in strip-line configuration having a top strip 62 of heavily doped GaAs to serve as an ohmic contact. The top strip 62 is bifurcated with prongs 64 and 66 extending longitudinally. A CsO_2 covered emission region 68 occupies the space between prongs 64 and 66 and extends over a 45 break 70 in a confining layer 72 that overlays substrate 74. The components of the cathode are as shown in FIG. 4. Suffice it to say that due to the configuration of the confining layer, photon emission is limited to the break in the confining layer so that electron emission is limited to the area between prongs 64 and 66 when an rf signal is applied between contact 62 and a conductive layer 76 underlying the substrate 74.

55 Referring to FIG. 3, it can be seen that the optoelectronic cold cathode electron emitter 60 forms an extension of strip-line 78 with strip 62 forming an extension of conductive strip 80 and the conductive layer 76 forming an extension of the conductive ground plane 82.

60 Strip-line 78, in turn, extends from strip-line 110 which is capacitively coupled to an input strip-line 86 having a top ground plane 88, a first dielectric layer 90, a conductive strip 92, second dielectric layer 94, and bottom ground plane 96. Dielectric layer 94, in fact, is

formed of two layers 98 and 100 with an extension 102 of conductive strip 80 extending partially along the interface between layers 98 and 100 as shown.

The forward end 106 of strip-line 86 is stepped downwardly with the top surface 108 of the stepped portion 5 forming a continuation of the top ground plane 88 of strip-line 86.

Strip-line 110 extends from the forward end of the stepped down portion 106. This strip-line has a top ground plane 112, first dielectric layer 114, conductive 10 strip 116 which forms an intermediate integral segment of conductive strip 80-102, second dielectric layer 118 which forms an extension of dielectric member 84, and a bottom ground plane 120 which forms an extension 15 of ground plane 82.

The input rf signal is applied between ground planes 88 and 96 and conductive layer 92. This signal is capacitively coupled (through the dielectric material) to strip extension 102 to appear on the prongs 64,66 or between the prongs 64,66 and the ground plane 76. As 20 before, an accelerating voltage 22 is applied to strip 62 (through a connector such as 122) to cause the emitted electrons to bombard the EBS diode.

In the above description, focusing electrodes 20 are disclosed to direct the emitted electrons to the EBS diode. It should be realized, however, that proximity focusing may be employed in place of the focusing electrode by providing suitable dielectric spacers to maintain the cold cathode and diode in the proper physical relationship for direct electron bombardment. 25

Thus, in accordance with the above, the above stated object is effectively attained.

Having thus described the invention, what is claimed is:

1. A solid state-vacuum wideband amplifier comprising, 35

a wideband rf signal input means, a strip-line for connection to an rf signal source, an rf responsive cold cathode electron source, a strip-line connected to said electron source, said strip-lines being capacitively coupled whereby said cathode emits electrons in response to rf from said source, an electron beam semiconductor current amplifying device responsive to incident bombarding electrons to generate an amplified current directly responsive to the bombarding electrons, means for accelerating electrons emitted by said source toward said electron beam semiconductor current amplifying device, means for focusing emitted electrons to bombard said semiconductor current amplifying device, and wideband rf signal output means connected to said current amplifying device.

2. The amplifier in accordance with claim 1 wherein 20 said cold cathode electron source comprises an elongated member of dielectric material, an SnO_2 layer overlying a surface of said elongated member; a first conductive comb overlying said layer, and a second conductive comb overlying said layer, the teeth of said 25 combs being interdigitated with space between adjacent teeth of the two combs.

3. The amplifier in accordance with claim 1 wherein 30 said electron source comprises an optoelectronic cold cathode in strip-line configuration having a top strip with a portion consisting of heavily doped GaAs to serve as an ohmic contact, said top strip portion includes a bifurcated portion having spaced apart prongs and said optoelectronic cold cathode further includes means for confining photons generated thereby to portions aligned with the spacing between said prongs whereby electrons are emitted between said prongs.
